(57) CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The broken lines immediately adjacent to the shaded area define the bounds of the claimed design and form no part thereof. The three different tones of grayscale shading represent a contrast in appearance only between their regions and do not represent any particular color. The broken lines depicting the remainder of the shoe show features that form no part of the claimed design.
